[57] **ABSTRACT**

The present invention relates to amidino ketones of the formula

wherein

R₁ is alkyl of 1 to 4 carbon atoms, phenyl or substituted phenyl, and

R₂ is alkyl of 1 to 4 carbon atoms, or

R₁ and R₂ together are $-(CH_2)_n-$, wherein n is an integer from 2 to 7,

and

R₃ is alkyl of 1 to 4 carbon atoms, or

R₁, R₂ and R₃ together with the carbon atom to which they are bound form the adamantly radical,

R₄ is alkyl of 1 to 8 carbon atoms, alkenyl of 2 to 8 carbon atoms, alkoxyalkyl of 2 to 8 carbon atoms in the aggregate thereof, cyanoalkyl wherein the alkyl radical is of 1 to 5 carbon atoms, or a group of formula

wherein

R₇ and R₈ are the same or different and each is alkyl of 1 to 4 carbon atoms, or

R₇ and R₈ together with the nitrogen atom are a heterocyclic ring, or a heterocyclic ring having a ring oxygen atom, and

R₅ and R₆ are the same or different and each is alkyl of 1 to 8 carbon atoms, alkenyl of 2 to 8 carbon atoms, alkoxyalkyl of 2 to 8 carbon atoms in the aggregate thereof or cyanoalkyl wherein the alkyl is of 1 to 5 carbon atoms, or one of R₄, R₅ and R₆ is phenyl or substituted phenyl and the others of R₄, R₅ and R₆ are as defined above, useful as hypoglycaemic agents.

2-KETOAMIDINES

IMPROVEMENTS IN OR RELATING TO ORGANIC COMPOUNDS

This application is a continuation-in-part of our co-pending application Ser. No. 366,681 filed June 4, 1973.

This present invention relates to amidino ketones, especially 3-oxo-butanamidine derivatives.

The invention provides compounds of formula I,

wherein

R₁ is alkyl of 1 to 4 carbon atoms, phenyl or substituted phenyl, and

R₂ is alkyl of 1 to 4 carbon atoms, or

R₁ and R₂ together are $-(CH_2)_n-$, wherein n is an integer from 2 to 7,

and

R₃ is alkyl of 1 to 4 carbon atoms, or

R₁, R₂ and R₃ together with the carbon atom to which they are bound form the adamantyl radical,

R₄ is alkyl of 1 to 8 carbon atoms, alkenyl of 2 to 8 carbon atoms, alkoxyalkyl of 2 to 8 carbon atoms in the aggregate thereof, cyanoalkyl wherein the alkyl radical is of 1 to 5 carbon atoms, or a group of formula

wherein

R₇ and R₈ are the same or different and each is alkyl of 1 to 4 carbon atoms, or

R₇ and R₈ together with the nitrogen atom are a heterocyclic ring, or a heterocyclic ring having a ring oxygen atom, and

R₅ and R₆ are the same or different and each is alkyl of 1 to 8 carbon atoms, alkenyl of 2 to 8 carbon atoms, alkoxyalkyl of 2 to 8 carbon atoms in the aggregate thereof or cyanoalkyl wherein the alkyl is of 1 to 5 carbon atoms, or one of R₄, R₅ and R₆ is phenyl or substituted phenyl and the others of R₄, R₅ and R₆ are as defined above.

When in formula I R₁ or one of the substituents R₄, R₅ and R₆ is a substituted phenyl group, the substituted phenyl group preferably is alkylphenyl, the alkyl radical having from 1 to 4 carbon atoms, especially methylphenyl, the alkyl substituent being preferably in the p position, or halophenyl, especially chlorophenyl, the halo substituent being preferably in the p position.

When R₇ and R₈ together with the nitrogen atom are a heterocyclic ring, this is preferably a five or six membered heterocyclic ring, preferably saturated e.g., morpholine, pyrrolidine or piperazine.

Further, in accordance with the invention a compound of formula I may be obtained by a process comprising desulphurizing a compound of formula II,

II

wherein R₁ to R₆ are as defined above.

The process according to the invention may be effected in the presence of a desulphurizing agent, preferably triaryl derivatives, trialkyl derivatives or mixed alkyl/triaryl derivatives wherein each of the alkyl groups preferably is of 1 to 4 carbon atoms, of phosphorous, arsenic, antimony or bismuth, especially, however, of phosphorus or arsenic. Especially preferred are the phosphorus derivatives. Preferred examples of desulphurizing agents are triphenylphosphine or arsine and triethyl-phosphite.

The process according to the invention may be effected in the absence of a solvent or in an inert organic solvent, e.g., dimethyl formamide, dioxane or dimethyl acetamide. However, the reaction is preferably effected in the absence of a solvent. The reaction temperature may be from 70° to 120°C. After the reaction is complete, the reaction mixture may be acidified, e.g., with an acid capable of forming a water-soluble acid addition salt form of the compound of formula I, e.g., hydrobromic acid, the residue is conveniently filtered off and the resulting acid addition salt form of the compound of formula I is conveniently isolated from the resulting reaction mixture in known manner, e.g., by concentrating by evaporation, and may be purified, e.g., by recrystallization.

Free base forms of compounds of formula I may be converted into acid addition salt form in conventional manner, and vice versa.

Examples of suitable acids for acid addition salt formation are the hydrohalic acids such as hydrochloric and hydrobromic acid, or perchloric acid, and organic acids such as oxalic acid and maleic acid.

The compounds of formula II, used as starting materials in the above process, may be obtained by reacting a reactive ester of an alcohol of formula III,

III

wherein R₁ to R₃ are as defined above, with a compound of formula IV,

IV

wherein R₄ to R₆ are as defined above.

In the above reaction the compounds of formula IV react in their tautomeric form of formula IVa,

wherein R₄ to R₆ are as defined above.

Suitable reactive esters of the alcohol of formula III, include esters of hydrohalic acids, e.g., hydrobromic or hydrochloric acid, or the tosylate. The reaction may be effected either in the absence of a solvent or in an inert organic solvent, e.g., a lower alcohol of 1 to 6 carbon atoms, acetone, or a cyclic or straight chain ether such as dioxane, tetrahydrofuran or diisopropyl ether. The reaction temperature conveniently is from 20° to 100°C. Free base forms of the resulting compounds of formula II are liberated from the acid addition salt forms in known manner, e.g., by treatment with an aqueous alkali metal hydroxide solution.

The compounds of formulae III and IV, used as starting materials in the above process, are either known or may be produced in known manner from known starting materials, for example a compound of formula IV wherein R₄, R₅ and R₆ are alkyl may be obtained by reacting an alkylisothiocyanate with a dialkyl amine in conventional manner.

In so far as the production of the starting material is not particularly described, these compounds are known or may be produced and purified in accordance with standard procedures.

The compounds of formula I are useful because they possess pharmacological activity in animals. In particular the compounds are useful as hypoglycaemic agents as indicated by a lowering of the blood sugar content in the blood of rats on p.o. administration of from 100 to 300 mg/kg animal body weight, of the compounds, in accordance with the following test:

The compound to be tested is administered in increasing doses to groups of 5 to 10 animals. 2 hours after administration, a blood sample is taken from each animal, and the glucose content in the blood serum is established using the ferric cyanide test. The blood sugar lowering effect is determined by a comparison with a control group of 5 to 10 animals to which is administered a physiological common salt solution.

For the above mentioned use the dosage will, of course, vary depending on the compound employed, mode of administration and condition to be treated. However, in general, satisfactory results are obtained when administered at a daily dosage of from 1.5 mg to about 300 mg per kg animal body weight, conveniently given in divided doses 2 to 4 times a day or in sustained release form. For the larger mammals, the total daily dosage is in the range from about 100 to about 1,000 mg, and dosage forms suitable for oral administration comprise from about 25 mg to about 500 mg of the compounds admixed with a solid or liquid pharmaceutical carrier or diluent.

Specific Examples of daily dosages, at which satisfactory results are obtained on p.o. administration are:

- i. Compound of Example 46 from 30 to 100 mg/kg animal body weight for rats, and for the larger mammals from about 100 mg to about 1,000 mg.
- ii. Compound of Example 14 from 30 to 100 mg/kg animal body weight for rats, and for the larger mammals from about 100 mg to about 1,000 mg; and
- iii. Compound of Example 68 from 30 to 100 mg/kg animal body weight for rats, and for the larger mammals from about 100 mg to about 1,000 mg.

As the free base forms of the compounds of formula I are usually oily at room temperature, the compounds are conveniently administered in pharmaceutically acceptable acid addition salt forms which have the same order of activity as the free base forms, and which are readily prepared in conventional manner. Representative acid addition salt forms include organic acid salt forms such as the hydrogen maleate, fumarate, tartrate and methane sulphonate and mineral acid salt forms such as the hydrochloride, hydrobromide and sulphate. A pharmaceutical composition may comprise a compound of formula I, in free base form or in pharmaceutically acceptable acid addition salt form, in association with a pharmaceutical carrier or diluent. Such compositions may be prepared by conventional techniques to be in the form of, for example, capsules, tablets, suppositories, suspensions or solutions, for enteral or parenteral administration. Aside from the usual pharmaceutical diluents or carriers, e.g., water, alcohols, natural or hardened oils and waxes, these pharmaceutical compositions may contain suitable preserving, stabilizing, wetting, solubilizing, sweetening, flavouring or colouring agents.

An example of a tablet composition comprises 136 mg of N¹-butyl-N²,N²-diallyl-4,4-dimethyl-3-oxo-pentanamidine hydrobromide, 1 mg of magnesium stearate, 4 mg of polyvinyl pyrrolidone, 0.5 mg of dimethyl silicone oil, 5 mg of talc, 10 mg of maize starch, 137.8 mg of lactose and 1.5 mg of polyethylene glycol - 6,000.

The tablets are produced in conventional manner and are provided with a double slit.

In a preferred class of compounds, R₁, R₂ and R₃ are independently alkyl, R₄ is alkyl, alkenyl, phenyl, or substituted phenyl and R₅ and R₆ are, independently, alkyl, alkenyl, alkoxyalkyl or cyanoalkyl. More especially R₁, R₂ and R₃ are alkyl, especially methyl, and R₄, R₅ and R₆ are independently alkenyl especially of 3 to 4 carbon atoms or especially alkyl of 1 to 4 carbon atoms.

In another preferred class of compounds R₅ and R₆ are identical.

In another class of compounds R₁ is phenyl or substituted phenyl and R₂ is alkyl, or R₁ and R₂ together are -(CH₂)_n- and R₃ is alkyl, or R₁, R₂ and R₃ together with the carbon atom to which they are bound form the adamantyl radical, R₄ is a group of formula;

65 wherein

R₇ and R₈ are the same or different and each is alkyl of 1 to 4 carbon atoms, or

R₇ and R₈ together with the nitrogen atom are a heterocyclic ring, or a heterocyclic ring having a ring oxygen atom, and

R₅ and R₆ are phenyl or substituted phenyl.

In the following non-limitative Examples the temperatures are indicated in degrees Centigrade, room temperature is between 20° and 30°C, unless otherwise indicated. The commonly used vacuum is between 8 and 20 mm of Hg, unless otherwise indicated.

EXAMPLE 1

N¹,N²,N²-triethyl-4,4-dimethyl-3-oxo-pentanamidine

a.

N¹,N²,N²-triethyl-5,5-dimethyl-4-oxo-2-thiahexanamidine

A mixture of 14.3 g of bromopinacoline, 12.8 g of N¹,N²,N²-triethyl thiourea and 120 cc of acetone is heated to the boil at reflux for 8 hours. The reaction mixture is subsequently concentrated by evaporation in a vacuum. 80 cc of an aqueous 1 N sodium hydroxide solution are added to the resulting residue, and the resulting mixture is extracted with diethyl ether. The ethereal solution is dried with potassium carbonate and is subsequently concentrated by evaporation. N¹,N²,N²-triethyl-5,5-dimethyl-4-oxo-2-thiahexanamidine is obtained as oily residue.

b. N¹,N²,N²-triethyl-4,4-dimethyl-3-oxo-pentanamidine

13.5 g of the oily N¹,N²,N²-triethyl-5,5-dimethyl-4-oxo-2-thiahexanamidine obtained in section (a) are mixed with 13.5 g of triphenyl phosphine, and the mixture is heated in an oil bath to 120° for 6 hours in a flask provided with an upright tube. The reaction mixture is subsequently cooled and triturated with 1 N hydrobromic acid until the acid reaction is maintained. The undissolved triphenyl phosphine sulphide is filtered off and washed with water. The aqueous filtrate is extracted with diethyl ether and purified with charcoal. After the charcoal is filtered off, the aqueous filtrate is evaporated to dryness in a vacuum. After recrystallization from 2 parts by volume of isopropanol/g of compound, or from 4.5 parts by volume of acetone/g of compound, the resulting N¹,N²,N²-triethyl-4,4-dimethyl-3-oxo-pentanamidine hydrobromide has a M.P. of 138°-140°.

Treatment of the hydrobromide with an aqueous 2 N sodium hydroxide solution, extraction of the alkaline solution with diethyl ether and concentration by evaporation of the ethereal mixture yields oily N¹,N²,N²-triethyl-4,4-dimethyl-3-oxo-pentanamidine.

EXAMPLE 2

N²,N²-di-isobutyl-N¹,4,4-trimethyl-3-oxo-pentanamidine.

a. N²,N²-di-isobutyl-N¹-methyl thiourea

A solution of 7.3 g of methyl isothiocyanate in 20 cc of benzene is added to a solution of 12.9 g of di-isobutylamine in 50 cc of benzene, and the resulting mixture is allowed to stand at 20° for 4 days. The mixture is subsequently concentrated by evaporation, and N²,N²-di-isobutyl-N¹-methyl thiourea, having a M.P. of 98°-100°, is obtained as residue.

10

b.

N²,N²-di-isobutyl-4-oxo-2-thia-N¹,5,5-trimethylhexanamidine hydrobromide

15 19.5 g of N²,N²-di-isobutyl-N¹-methyl thiourea are dissolved in 100 cc of acetone, and 17.3 g of bromopinacoline are added to the solution. The resulting mixture is allowed to stand at 20° for 12 hours. The mixture is subsequently heated to the boil for 4 hours, is subsequently cooled, and the resulting precipitate is filtered off. The N²,N²-di-isobutyl-4-oxo-2-thia-N¹,5,5-trimethylhexanamidine hydrobromide, obtained as filter residue, has a M.P. of 202°-204°.

25

c.

N²,N²-di-isobutyl-N¹,4,4-trimethyl-3-oxo-pentanamidine

11.8 g of N²,N²-di-isobutyl-4-oxo-2-thia-N¹,5,5-trimethylhexanamidine (obtained from the hydrobromide by treatment with caustic soda solution and extraction of the liberated base with ether) are heated to 120° for 8 hours together with 12.5 g of triphenyl arsine. The resulting melted material is neutralized with 1 N hydrobromic acid (about 28 cc). The aqueous solution is poured off and cold alcohol is added to the smearable crystalline product until the solid components are filterable. Filtration is subsequently effected. The filter residue contains about 11.6 g of a mixture of triphenyl arsine and triphenyl arsine sulphide. The filtrate is extracted with 100 cc of diethyl ether, and the aqueous solution is concentrated by evaporation in a vacuum. The evaporation residue is heated to 80° together with 150 cc of ethyl acetate, whereby after initial solution crystals are formed. Cooling is then effected to 0°, and the residue N²,N²-di-isobutyl-N¹,4,4-trimethyl-3-oxo-pentanamidine hydrobromide (M.P. 151°-156°) is filtered off.

50 The compounds of formula I, indicated in the following Tables, are obtained by using the processes exemplified in the above Examples 1 and 2 and the corresponding starting materials. The indicated melting points refer to the corresponding salt forms. The free base forms of the compounds of formula I are obtained from the salt forms in known manner, e.g., by treatment with caustic soda solution and extraction with ether.

55 The substituents are in the ω -position except where otherwise stated.

103	Adamantyl	Adamantyl	Adamantyl	Ethyl	Ethyl	240-242°	Bromide	

Using the process exemplified in Example 1 or 2 and the appropriate starting materials, there are obtained the following compounds

What is claimed is:

1. A compound of the formula:

wherein

R₁ is alkyl of 1 to 4 carbon atoms, phenyl, substituted with halo or alkyl of 1 to 4 carbon atoms, and

15 R₂ is alkyl of 1 to 4 carbon atoms, or

R₁ and R₂ together are $-(CH_2)_n-$, wherein n is an integer from 2 to 7,

and

20 R₃ is alkyl of 1 to 4 carbon atoms,

R₄ is alkyl of 1 to 8 carbon atoms, alkenyl of 2 to 8 carbon atoms, and

25 R₅ and R₆ are the same or different and each is alkyl of 1 to 8 carbon atoms, alkenyl of 2 to 8 carbon atoms, or one of R₄, R₅ and R₆ is phenyl or phenyl substituted with halo or alkyl of 1 to 4 carbon atoms and the others of R₄, R₅ and R₆ are as defined above,

or a salt thereof of a pharmaceutically acceptable acid.

30 2. A compound of the formula:

wherein

40 R₁ is alkyl of 1 to 4 carbon atoms, phenyl or phenyl mono-substituted with chloro or alkyl of 1 to 4 carbon atoms, and

R₂ is alkyl of 1 to 4 carbon atoms, or

R₁ and R₂ together are $-(CH_2)_n-$, wherein n is an integer from 2 to 7,

and

45 R₃ is alkyl of 1 to 4 carbon atoms,

R₄ is alkyl of 1 to 8 carbon atoms, or alkenyl of 2 to 8 carbon atoms and

50 R₅ and R₆ are the same or different and each is alkyl of 1 to 8 carbon atoms or alkenyl of 2 to 8 carbon atoms or

one of R₄, R₅ and R₆ is phenyl or phenyl mono-substituted with chloro or alkyl of 1 to 4 carbon atoms and the others of R₄, R₅ and R₆ are as defined above,

55 or a salt thereof of a pharmaceutically acceptable acid.

3. A compound of claim 2, wherein R₁, R₂ and R₃ are, independently alkyl and R₄, R₅ and R₆ are, independently, alkenyl or alkyl.

60 4. The compound of claim 3, which is N¹,N²-triethyl-4,4-dimethyl-3-oxo-pentanamidine.

5. The compound of claim 3, which is N²,N²-diisobutyl-N¹,4,4-trimethyl-3-oxo-pentanamidine.

6. A compound of claim 2, wherein R₁, R₂ and R₃ are methyl.

7. The compound of claim 6, wherein R_4 is methyl, R_5 is methyl and R_6 is methyl.
8. The compound of claim 6, wherein R_4 is methyl, R_5 is methyl and R_6 is ethyl.
9. The compound of claim 6, wherein R_4 is methyl, R_5 is ethyl and R_6 is ethyl.
10. The compound of claim 6, wherein R_4 is methyl, R_5 is propyl and R_6 is propyl.
11. The compound of claim 6, wherein R_4 is methyl, R_5 is isopropyl and R_6 is isopropyl.
12. The compound of claim 6, wherein R_4 is methyl, R_5 is allyl and R_6 is allyl.
13. The compound of claim 6, wherein R_4 is methyl, R_5 is butyl and R_6 is butyl.
14. The compound of claim 6, wherein R_4 is methyl, R_5 is isobutyl and R_6 is isobutyl.
15. The compound of claim 6, wherein R_4 is ethyl, R_5 is methyl and R_6 methyl.
16. The compound of claim 6, wherein R_4 is ethyl, R_5 20 is methyl and R_6 is ethyl.
17. The compound of claim 6, wherein R_4 is ethyl, R_5 is propyl and R_6 is propyl.
18. The compound of claim 6, wherein R_4 is ethyl, R_5 25 is isopropyl and R_6 is isopropyl.
19. The compound of claim 6, wherein R_4 is ethyl, R_5 is butyl and R_6 is butyl.
20. The compound of claim 6, wherein R_4 is ethyl, R_5 30 is isobutyl and R_6 is isobutyl.
21. The compound of claim 6, wherein R_4 is ethyl, R_5 is allyl and R_6 is allyl.
22. The compound of claim 6, wherein R_4 is propyl, R_5 35 is methyl and R_6 is methyl.
23. The compound of claim 6, wherein R_4 is propyl, R_5 is ethyl and R_6 is ethyl.
24. The compound of claim 6, wherein R_4 is propyl, R_5 40 is propyl and R_6 is propyl.
25. The compound of claim 6, wherein R_4 is propyl, R_5 is isopropyl and R_6 is isopropyl.
26. The compound of claim 6, wherein R_4 is propyl, R_5 45 is isobutyl and R_6 is isobutyl.
27. The compound of claim 6, wherein R_4 is propyl, R_5 is allyl and R_6 is allyl.
28. The compound of claim 6, wherein R_4 is isopropyl, R_5 50 is ethyl and R_6 is ethyl.
29. The compound of claim 6, wherein R_4 is isopropyl, R_5 is propyl and R_6 is propyl.
30. The compound of claim 6, wherein R_4 is isopropyl, R_5 55 is isopropyl and R_6 is isopropyl.
31. The compound of claim 6, wherein R_4 is isopropyl, R_5 is allyl and R_6 is allyl.
32. The compound of claim 6, wherein R_4 is allyl, R_5 60 is methyl and R_6 is methyl.
33. The compound of claim 6, wherein R_4 is allyl, R_5 is ethyl and R_6 is ethyl.
34. The compound of claim 6, wherein R_4 is allyl, R_5 is propyl and R_6 is propyl.
35. The compound of claim 6, wherein R_4 is allyl, R_5 65 is isopropyl and R_6 is isopropyl.
36. The compound of claim 6, wherein R_4 is allyl, R_5 is isobutyl and R_6 is isobutyl.
37. The compound of claim 6, wherein R_4 is allyl, R_5 is allyl and R_6 is allyl.
38. The compound of claim 6, wherein R_4 is butyl, R_5 70 is methyl and R_6 is methyl.
39. The compound of claim 6, wherein R_4 is butyl, R_5 is ethyl and R_6 is ethyl.

40. The compound of claim 6, wherein R_4 is butyl, R_5 is propyl and R_6 is propyl.
41. The compound of claim 6, wherein R_4 is butyl, R_5 is isopropyl and R_6 is isopropyl.
42. The compound of claim 6, wherein R_4 is butyl, R_5 is butyl and R_6 is butyl.
43. The compound of claim 6, wherein R_4 is butyl, R_5 is allyl and R_6 is allyl.
44. The compound of claim 6, wherein R_4 is isobutyl, R_5 10 is ethyl and R_6 is ethyl.
45. The compound of claim 6, wherein R_4 is isobutyl, R_5 is propyl and R_6 is propyl.
46. The compound of claim 6, wherein R_4 is isobutyl, R_5 is allyl and R_6 is allyl.
47. The compound of claim 6, wherein R_4 is sec-butyl, R_5 is ethyl and R_6 is ethyl.
48. The compound of claim 6, wherein R_4 is sec-butyl, R_5 is propyl and R_6 is propyl.
49. The compound of claim 6, wherein R_4 is sec-butyl, R_5 is allyl and R_6 is allyl.
50. The compound of claim 6, wherein R_4 is tert-butyl, R_5 is ethyl and R_6 is ethyl.
51. The compound of claim 6, wherein R_4 is tert-butyl, R_5 is isopropyl and R_6 is isopropyl.
52. The compound of claim 6, wherein R_4 is amyl, R_5 is methyl and R_6 is methyl.
53. The compound of claim 6, wherein R_4 is amyl, R_5 is ethyl and R_6 is ethyl.
54. The compound of claim 6, wherein R_4 is amyl, R_5 is propyl and R_6 is propyl.
55. The compound of claim 6, wherein R_4 is amyl, R_5 is allyl and R_6 allyl.
56. The compound of claim 6, wherein R_4 is isoamyl, R_5 35 is ethyl and R_6 is ethyl.
57. The compound of claim 6, wherein R_4 is octyl, R_5 is ethyl and R_6 is ethyl.
58. The compound of claim 6, wherein R_4 is methyl, R_5 is methyl and R_6 phenyl.
59. The compound of claim 6, wherein R_4 is ethyl, R_5 is ethyl and R_6 is phenyl.
60. The compound of claim 6, wherein R_4 is phenyl, R_5 is methyl and R_6 is methyl.
61. The compound of claim 6, wherein R_4 is phenyl, R_5 60 is ethyl and R_6 is ethyl.
62. The compound of claim 6, wherein R_4 is phenyl, R_5 is propyl and R_6 is propyl.
63. The compound of claim 6, wherein R_4 is phenyl, R_5 is allyl and R_6 is allyl.
64. The compound of claim 6, wherein R_4 is p-Cl-phenyl, R_5 is ethyl and R_6 is ethyl.
65. The compound of claim 6, wherein R_4 is p-CH₃-phenyl, R_5 is ethyl and R_6 is ethyl.
66. The compound of claim 6, wherein R_4 is sec-butyl, R_5 is isopropyl and R_6 is isopropyl.
67. The compound of claim 6, wherein R_4 is octyl, R_5 is methyl and R_6 is methyl.
68. The compound of claim 6, wherein R_4 is β -methylallyl, R_5 is methyl and R_6 is methyl.
69. The compound of claim 6, wherein R_4 is β -methylallyl, R_5 is ethyl and R_6 is ethyl.
70. The compound of claim 6, wherein R_5 is β -methylallyl, R_5 is propyl and R_6 is propyl.
71. The compound of claim 6, wherein R_4 is hexyl, R_5 is ethyl and R_6 is ethyl.
72. The compound of claim 6, wherein R_4 is butyl, R_5 is methyl and R_6 is ethyl.

73. The compound of claim 6, wherein R₄ is hexyl, R₅ is methyl and R₆ is methyl.

74. The compound of claim 6, wherein R₄ is isobutyl, R₅ is methyl and R₆ is methyl.

75. The compound of claim 6, wherein R₄ is sec-butyl, R₅ is methyl and R₆ is ethyl.

76. The compound of claim 6, wherein R₄ is tert-butyl, R₅ is methyl and R₆ is ethyl.

77. The compound of claim 6, wherein R₄ is sec-hexyl, R₅ is methyl and R₆ is methyl.

78. The compound of claim 6, wherein R₄ is methyl, R₅ is isoamyl and R₆ is isoamyl.

79. The compound of claim 6, wherein R₄ is isoamyl, R₅ is allyl and R₆ is allyl.

80. The compound of claim 6, wherein R₄ is sec-hexyl, R₅ is methyl and R₆ is ethyl.

81. A compound of claim 2, wherein R₁ and R₂ are methyl and R₃ is ethyl.

82. The compound of claim 81, wherein R₄ is ethyl, R₅ is ethyl and R₆ is ethyl.

83. The compound of claim 81, wherein R₄ is methyl, R₅ is isobutyl and R₆ is isobutyl.

84. The compound of claim 81, wherein R₄ is ethyl, R₅ is propyl and R₆ is propyl.

85. The compound of claim 81, wherein R₄ is ethyl, R₅ is allyl and R₆ is allyl.

86. The compound of claim 81, wherein R₄ is sec-butyl, R₅ is ethyl and R₆ ethyl.

87. The compound of claim 81, wherein R₄ is butyl, R₅ is ethyl and R₆ is ethyl.

88. The compound of claim 81, wherein R₄ is sec-butyl, R₅ is allyl and R₆ is allyl.

89. The compound of claim 2, wherein R₁, R₃ and R₄ are methyl, R₂ is butyl and R₅ and R₆ are sec-butyl.

90. The compound of claim 2, wherein R₁, R₃ and R₄ are methyl, R₂ is butyl and R₅ and R₆ are isobutyl.

91. The compound of claim 2, wherein R₁ and R₃ are methyl, R₂ is butyl and R₄, R₅ and R₆ are ethyl.

92. The compound of claim 2, wherein R₁ and R₃ are methyl, R₂ is butyl, R₄ is tert-butyl and R₅ and R₆ are ethyl.

93. The compound of claim 2, wherein R₁ to R₆ are ethyl.

94. The compound of claim 2, wherein R₁, R₂, R₃, R₅ and R₆ are ethyl and R₄ is sec-butyl.

95. The compound of claim 2, wherein R₁ to R₃ are ethyl, R₄ is methyl and R₅ and R₆ are sec-butyl.

96. The compound of claim 2, wherein R₁ and R₃ are methyl, R₂ is butyl, R₄ is sec-butyl and R₅ and R₆ are ethyl.

97. The compound of claim 2, wherein R₁ to R₃ are ethyl, R₄ is methyl and R₅ and R₆ are isobutyl.
